(57) **CLAIM**

The ornamental design for a dental restoration placement tray, as shown and described.

DESCRIPTION

FIG. 1 is a right perspective view of the dental restoration placement tray, showing my new design;
FIG. 2 is a front elevation view thereof;
FIG. 3 is a rear elevation view thereof;
FIG. 4 is a right side elevation view thereof;
FIG. 5 is a top plan view thereof;
FIG. 6 is a bottom plan view thereof;
FIG. 7 is a left perspective view thereof;
FIG. 8 is a left side elevation view thereof; and,
FIG. 9 is an environmental view thereof showing an example use thereof on an example tooth mold with example veneers.

The broken lines of even length in FIGS. 1-9 depict portions of the dental restoration placement tray that form no part of the claimed design, and the additional broken lines of even length in FIG. 9 depict environmental features of an example tooth mold with example veneers that form no part of the claimed design. The dash-dot-dash broken lines define boundary lines that form no part of the claimed design.
